JOSEPH G. WILLEKE, OF SEATTLE, WASHINGTON.

DESIGN FOR A CABINET FOR PHONOGRAPHS OR LIKE MACHINES.

54,228.

Specification for Design.

Patented Nov. 18, 1919.

Application filed August 5, 1919. Serial No. 315,545. Term of patent 14 years.

To all whom it may concern:

Be it known that I, JOSEPH GEORGE WILLEKE, residing at Seattle, in the county of King and State of Washington, have invented a new, original and ornamental Design for Phonograph-Cabinets, of which the following is a specification, reference being had to the accompanying drawing, forming a part thereof.

The accompanying drawing is a perspective view of a phonograph or like machine, showing my new design, the plan view of which is symmetrical.

I claim:

The ornamental design for a cabinet for phonographs or like machines, as shown.

In testimony whereof, I have signed my name to this specification in the presence of two subscribing witnesses, this 24 day of July, 1919.

JOSEPH G. WILLEKE.
